UNITED STATES PATENT OFFICE

2,589,284

DRIER

Charles S. O'Neil, Two Rivers, Wis., assignor to
Hamilton Manufacturing Company, Two Rivers, Wis., a corporation of Wisconsin

Application September 20, 1946, Serial No. 698,240

7 Claims. (Cl. 34—77)

1

The invention relates generally to laundry dryers and more particularly to a laundry dryer of the type in which the laundry is tumbled in the presence of heat to remove moisture therefrom.

The general object of the invention is to provide a novel dryer of the foregoing type, which is capable of drying the laundry quickly and at a relatively low operating cost, and which is relatively inexpensive to produce on a quantity basis.

Another important object is to provide a novel dryer of the foregoing type, comprising a casing with means therein providing a drying chamber through which heated air is circulated, such air after passing through the drying chamber being discharged into the space between the casing and said means, where a major portion of the moisture in the air is condensed and the air is then returned for reheating and recirculation through the drying chamber.

A further object is to provide a novel dryer in which the means providing the drying chamber is in the form of a rotating drum and is provided with elements on its periphery for stirring the air within the casing so that it will thoroughly contact the casing walls to cause a maximum condensation.

Still another object is to provide a novel dryer in which the air discharged from the drying chamber is passed through a means located within the casing for substantially reducing the temperature of the air to cause condensation of a major portion of the moisture content of the air.

Other objects and advantages will become apparent from the following description taken in connection with the accompanying drawings, in which:

Figure 1 is a front elevational view of a dryer embodying the features of the invention.

Fig. 2 is a vertical sectional view taken on the line 2—2 of Fig. 1.

Fig. 3 is a fragmentary front elevational view similar to Fig. 1 but showing a modified form of dryer.

Fig. 4 is a fragmentary vertical sectional view taken on the line 4—4 of Fig. 3.

As heretofore mentioned, the present invention relates to a laundry dryer in which the laundry is tumbled in the presence of heat to remove moisture therefrom. To this end, the laundry is placed in the drying chamber and air is circulated therethrough to carry away the moisture as it evaporates from the laundry. In order to prevent dust from being carried into the laundry while it is being dried by air taken from the outside of the machine, it is preferable to recircu-

2

late the air within the machine so that the only dirt that can be carried into the laundry will be that suspended in the air within the machine at the time the drying operation is started. However, to effectively dry the laundry, the air discharged from the drying chamber of the machine must have its moisture content reduced before the air is recirculated through the drying chamber.

The present machine provides for operation in 10 the manner set forth above and, to this end, comprises generally a casing structure within which, in spaced relation thereto, is mounted a rotatable drum constituting the drying chamber and in which the laundry is placed. The drum is substantially closed to the outside air but is provided with an intake and an outlet communicating with the space between the drum and the casing. The dryer also includes means for drawing air through the intake from said space into 20 the drum and for discharging such air, after it becomes moisture laden, into said space, the air as it enters the drum being heated to increase its moisture absorbing capacity and thus facilitate the drying operation. The air, in circulating through the space between the drum and the casing, comes in contact with the relatively cool outer walls of the casing (such walls being cooled either naturally or by forced cooling) and is reduced in temperature by such contact to an extent sufficient to cause condensation of a portion of the moisture content of the air. Thus, when the air is re-introduced into 30 the drum and heated, it will have sufficient moisture absorbing capacity to effect further drying 35 of the laundry.

The drum is adapted to be rotatably driven to tumble the laundry during the drying operation and thus expose all portions thereof to the air, and the drum is provided with means on its exterior to stir the air discharged from the drum into the space between the drum and the casing so that the contact of such air with the casing is thereby increased and a maximum condensation takes place.

In the modified form shown in Figs. 3 and 4 of the drawings, instead of relying solely on the condensing action of bringing the air discharged from the drum into contact with the outside casing, a condensing means is mounted within the space between the drum and the outside casing. With this construction, air as it is discharged from the drum, first passes through the condensing means where the air is positively cooled 50 by spraying a cooling fluid therein and a major

portion of the moisture content of the air is thus condensed. The air then passes from the condensing means into the space between the drum and outside casing to contact with the outer casing for further cooling and condensing action before it is recirculated through the drum.

The preferred embodiment of the invention shown in Figs. 1 and 2 comprises an outer casing indicated generally at 10. Preferably, the casing 10 is rectilinear in form and has a flat top wall 11, a front wall 12, a rear wall 13, as well as side and bottom walls. Extending parallel to the rear wall 13 but spaced therefrom is a transverse partition 14, and mounted in the space between the front wall 12 and the partition 14 is means providing a drying chamber which, in the present instance, constitutes a drum indicated generally at 15. The drum 15 is preferably cylindrical in form with its axis horizontal, and is of such size as to provide a substantial space between the drum and the surrounding walls of the casing 10.

The drum 15 is insulated on its peripheral and end walls to prevent radiation of heat therefrom into the space within the casing 10, and is provided at its ends with axially extending annular flanges 16 and 17. The flange 16 at the front end of the drum registers with an annular opening 20 in the front wall 12 of the casing 10 to provide for access to the interior of the drum whereby the laundry may be inserted in and withdrawn from the drum. The opening through the annular flange 16 is adapted to be closed by a door 21 hingedly mounted on the front wall 12 of the casing, the door 21 when closed providing a substantially airtight seal so that no substantial circulation of air can take place therethrough when the machine is in operation. A removable lint catcher in the form of a screen 22 may be placed within the opening of the flange 16. The rear annular flange 17 extends through an opening 23 provided in the transverse partition 14.

The drum is rotatably supported in the above-described position by any suitable means, but preferably by a unitary supporting structure comprising a base 24 having uprights 25 and 26 at its front and rear ends. The uprights 25 and 26 preferably are provided with rollers 27 on which the annular flanges 16 and 17 are rotatably mounted, thus supporting the drum 15 at its opposite ends.

Air is adapted to be circulated within the drum, preferably by means of a fan 30 mounted coaxially therewith adjacent the rear end thereof. To prevent the laundry from becoming entangled with the fan 30, a perforated dome-shaped guard 31 may be provided to enclose the blades of the fan 30. The fan 30 is preferably mounted directly on the front end of the shaft 32 of a drive motor 33 supported within the annular flange 17 by a bracket 34 rigidly secured to the rear upright 26. The motor 33 is also utilized to rotatably drive the drum 15 and, to this end, is provided with a pulley 35 on the rear end of the motor shaft, connected by a belt 36 to a pulley 37 carried on a shaft supported in a spring-mounted bracket 38 carried on the rear upright 26. Mounted on the same shaft with the pulley 37 is a second pulley 40 driving a belt 41 extending over the annular flange 17 and held between annular guide ribs 42 thereon. The annular flange 17 thus serves as a pulley constituting part of the drive for the drum 15.

As heretofore mentioned, the air circulated through the drying chamber by the fan 30 is adapted to be discharged from the drum into the space between the drum and the outer casing 10 where the moisture content thereof is to a great extent condensed, and the air is then recirculated through the drum. The interior of the drum is preferably provided with a plurality of inwardly extending ribs 43 by which the laundry is adapted to be tumbled during the drying operation to expose all portions thereof uniformly to the drying action of the air circulated within the drum. To provide for the recirculation of the air, the annular flanges 16 and 17 are provided with radial openings 44 located so as to communicate with the space between the drum and the casing 10. Thus, during the operation of the machine, the fan 30 will cause circulation of air within the drying chamber and will force some of such air forwardly through the annular flange 16 where any lint in the air will be caught by the lint catcher 22. The air will then be discharged radially through the openings 44 in the flange 16. The air so discharged into this space will contact the outer walls of the casing and, since they are substantially at the temperature of the outside air, the air within the casing will thereby be cooled and a portion of the moisture content thereof will be condensed. The condensation will settle on the walls of the casing 10 and will drain downwardly to the base thereof where it may be discharged through a drain pipe 45. To insure having such air come in thorough contact with the casing walls, the outer periphery of the drum 15 may be provided with a plurality of radially extending blades 46 to stir the air within the space between the drum and the casing and thus force the air into contact with the casing walls.

After the air is circulated within such space and has had a portion of its moisture content condensed therefrom, the air is then drawn inwardly through the openings 44 in the flange 17 for recirculation within the drying chamber by the fan 30. On passing through the openings 44 in the annular flange 17, the air passes through an electrical heating element 47 to substantially raise its temperature and thus increase its moisture carrying capacity and to provide the heat required for the latent heat of evaporation of the moisture, before circulation within the drying chamber. Preferably, a plate 50 is mounted within the annular flange 17 between the motor 33 and the heating element 47 to prevent radiation of heat from the element onto the motor and to substantially cut off inflow of air through the outer end of the annular flange 17. The small opening provided through the plate 50, through which the motor shaft 32 and the leads for the heating element 47 extend, is rendered substantially ineffective to permit flow of air since the door 21 seals the only other opening into the outer casing and drying chamber and thus prevents egress of air to the outside and consequent ingress of air through the plate 50.

In the modified form of structure shown in Figs. 3 and 4, further means is provided for effecting condensation of the moisture content of the air discharged from the front end of the drum through the radial openings 44 in the annular flange 16. Such means preferably comprises a duct 51 formed of sheet metal and extending upwardly about the flange 16 to enclose the openings 44. Thus, air discharged through the openings 44 is carried through the duct 51 and may be

discharged therefrom into the space between the drum and the casing 10 through vents 52 provided in the lower portion of the duct 51. Preferably, in this embodiment of the invention, the front upright 25 is provided with a cut-out area 53 within which area the vents 52 are located so that air may be freely discharged from the duct into the space between the drum and the casing. To cool the air as it passes through the duct 51, a spraying means 54 is provided within the duct 51 for spraying cooling fluid downwardly through the air as it passes through the duct. Thus, the cooling fluid will substantially lower the temperature of the air discharged from the drying chamber to condense a major portion of the moisture content thereof, and the cooling fluid as well as the condensate may be drawn off through a discharge pipe 55 located at the lower end of the duct 51. The air, after being thus cooled and having a portion of its moisture content removed, is discharged into the space between the drum and the casing 10, where it will further contact with the outer wall surfaces of the casing 10 to effect further cooling of the air and condensation of its moisture content if the cooling effect of the spray within the duct 51 has not been sufficient to lower the air to the temperature of the walls of the outside casing 10. The air, after passing through the space between the drum and the casing 10, is then drawn inwardly through the openings 44 of the flange 17, as in the case of the previously described embodiment of the invention, for reheating and then recirculation through the drying chamber.

I claim:

1. A laundry dryer comprising a non-insulating casing, a rotatable drum mounted within said casing in spaced relation thereto, said drum having intake and outlet openings both communicating with the space between said casing and said drum, and said space providing communication from said outlet to said inlet outside of said drum but within said casing, a fan located in said drum for drawing air into said drum through said intake from said space and for discharging air from said drum through said outlet to said space, and a heater mounted in said intake to heat the air drawn therethrough, the air discharged through said outlet being reduced in temperature in passing through said space to condense a portion of the moisture therein before recirculation through and reheating in said drum.

2. A laundry dryer comprising a closed non-insulating casing, a generally cylindrical drum positioned within said casing in spaced relation thereto and with the axis of the drum horizontal, means for rotatably supporting and driving said drum, said drum having annular flanges projecting from its opposite ends and both flanges having radial perforations to provide communication at both ends of the drum with the space between said drum and said casing, means for drawing air into said drum from said space through the radial perforations of one of said flanges and for discharging air from said drum to said space through the radial perforations of the other of said flanges, and means located in said one flange for heating the air as it is drawn into said drum.

3. A laundry dryer comprising a non-insulating casing, a generally cylindrical drum positioned within said casing in spaced relation thereto and with the axis of the drum horizontal, said drum having annular flanges of smaller diameter than the drum projecting from its opposite ends and

perforated to provide communication at both ends of the drum with the space between said drum and said casing, means engaging said flanges for rotatably supporting said drum, a fan located in said drum for drawing air through the perforations of one of said flanges and for discharging air through the perforations of the other flange, means located in said one flange for heating the air as it is drawn into said drum, and means connected to one of said flanges for driving the drum.

4. A laundry dryer comprising a closed non-insulating casing, a rotatably driven drum mounted within said casing in spaced relation thereto, means for drawing air into said drum from the space between said drum and said casing and for discharging air from said drum into said space, means located at the point where the air is admitted to the drum for heating the air as it enters said drum, the air discharged from said drum being cooled by contact against said casing to condense moisture therefrom, and means on said drum for stirring the air in said space to increase contact thereof with said casing.

5. A laundry dryer comprising a closed non-insulating casing, a rotatably driven drum mounted within said casing in spaced relation thereto, means for drawing air into said drum from the space between said drum and said casing and for discharging air from said drum into said space, means located at the point where the air is admitted to the drum for heating the air as it enters said drum, the air discharged from said drum being cooled by contact against said casing to condense moisture therefrom, and a plurality of blades mounted on the periphery of said drum for stirring the air in said space to increase contact thereof with said casing.

6. A laundry dryer comprising a casing, a generally cylindrical drum mounted with its axis horizontal in said casing in spaced relation thereto and having a pair of annular flanges at its ends provided with radial perforations located in the space at the ends of the drum between the drum and the casing, heating means within one of said flanges, means for drawing air into the drum from said space through the perforations in said one flange and for discharging air from the drum through the perforations of the other flange, a duct extending around the last-mentioned flange to receive the air discharged through the perforations thereof and being apertured to discharge the air into said space, and means in said duct for condensing moisture from said air.

7. A laundry dryer comprising a casing, a generally cylindrical drum mounted with its axis horizontal in said casing in spaced relation thereto and having a pair of annular flanges at its ends provided with radial perforations located in the space at the ends of the drum between the drum and the casing, heating means within one of said flanges, means for drawing air into the drum from said space through the perforations in said one flange and for discharging air from the drum through the perforations of the other flange, a support of plate-like form having a pair of rollers rotatably supporting the last-mentioned flange and having a cut-out area in its lower portion, a box-like duct interposed between the casing wall and said support and having its upper end extending about said last-mentioned flange to receive the air discharged through the perforations thereof, said duct having vents located in said cut-out area for discharge of the air into said

space, and means in said duct for condensing moisture from said air.
